United States Patent

Des. 240,428
Patented July 6, 1976

240,428

PIPE ADAPTER

John J. Hoffman, South Bend, Ind., assignor to Jackel
Company, Inc., South Bend, Ind.

Filed Nov. 13, 1974, Ser. No. 523,243

Term of patent 14 years

Int. Cl. D23—01

U.S. Cl. D23—40

Fig. 1

Fig. 2

Fig. 3

Fig. 4

Fig. 5

Fig. 6

FIG. 1 is a perspective view of a pipe adapter embodying my new design;

FIG. 2 is a front elevational view;

FIG. 3 is a side elevational view;

FIG. 4 is a rear elevational view;

FIG. 5 is an elevational view of the side opposite that shown in FIG. 3; and

FIG. 6 is an elevational view taken 90 degrees from FIG. 5.

I claim:

The ornamental design for a pipe adapter, substantially as shown.
